UNITED STATES PATENT OFFICE

DAVID GESTETNER, OF TOTTENHAM HALE, LONDON, ENGLAND, ASSIGNOR, BY MESNE ASSIGNMENTS, TO A. B. DICK COMPANY, OF CHICAGO, ILLINOIS, A CORPORATION OF ILLINOIS

DUPLICATING MACHINE

Application filed December 23, 1930, Serial No. 504,366, and in Great Britain February 1, 1930.

This invention relates to duplicating machines of the kind in which with a plurality of inking cylinders there is associated a flexible stencil carrier secured to endless bands whereby the stencil is caused to travel over the inking cylinders.

The object of the invention is to provide means adapted to facilitate the cleaning, that is to say, the removal of ink from the inking cylinders.

The invention consists, broadly, in means for removing ink from the inking cylinders of duplicating machines of the kind above referred to comprising a scraper element in the form of a strip of flexible material, the opposite edges of which are adapted to bear against the inking cylinders, a rigid support for the scraper element, arms associated with the rigid support adapted to be brought in position to bear against some stationary portion of the duplicating machine and further arms on the rigid support adapted to extend between the inking cylinders to resist rotational motion being imparted to the device consequent upon rotation of the inking cylinders.

Conveniently, the arms adapted to engage some stationary portion of the machine are provided on the ends of rods slidably mounted in guides in the frame member of the cleaning device and adapted to be axially moved to bring the arms into and out of position to engage some stationary portion of the machine and, preferably, to be rotated about their axes to press the scraper element against the inking cylinders.

Thus, for instance, the guides for the rods may be tubular and be provided with slots similar to those provided in a bolt, means being provided on the rods adapted to co-operate with the slots and function as means for imparting motion to the rods and for securing the same in position to retain the scraper element in contact with the inking cylinders.

The ends of the arms are conveniently recessed particularly when they are designed to engage against the arms provided in the construction of duplicating machine described in the specification of application for Letters Patent No. 440,518 filed on the 31st day of

March, 1930, for engaging and locating the waver rollers with respect to the inking cylinders.

Preferably, the scraper element is arranged to be detachably connected with the frame member and it may consist of a strip of fibre or felted fabric such as thick paper wholly or in part coated or covered with a thin sheet of india-rubber or with some other composition, for instance, a gelatine composition which is impermeable to ink.

The invention will be described further in detail as applied to a stencil duplicating machine in accordance with the above-mentioned application with reference to the accompanying drawings, in which:

Figure 1 is a view in elevation of a cleaning or ink-removing device in accordance with the invention;

Figure 2 is a corresponding plan view;

Figure 3 is a front elevation of a detail,

namely, the element functioning as a scraper for removing the ink,

Figure 4 being a corresponding end elevation;

Figure 5 is a fragmentary view of a duplicating machine with the cleaning or ink-removing device in position;

Figure 6 is a fragmentary view of a duplicating machine with the cleaning or ink-removing device in position thereon viewed in the direction of the arrow VI in Figure 7, which is a corresponding end elevation viewed in the direction of the arrow VII in the mutilated plan view, Figure 8.

In the drawings, 1 is the scraper element, the edges 2 of which are coated with a composition, such for example as a gelatine composition, adapted to render the edges of the scraper element impermeable to ink and to provide a smooth bearing between the edges and the inking cylinders.

This scraper element is provided with a plurality of holes 3 and with recesses 4 in its ends, the holes being provided to engage the pins 5 and the recesses to engage the arms 6 formed on the frame member functioning as a support for the scraper element. With the frame member there is associated a member 7 which, in the construction illustrated is

formed of a strip of sheet metal suitably bent so that its opposite sides may engage about the portion 8 of the frame member extending between the arms above referred to, thus forming with the adjacent portion of the frame member a tubular guide within which there are slidably arranged two rods 9 and 9a provided with loops 10 and 10a functioning as handles whereby they may be moved longitudinally within the tubular guide.

In the member 8 there are provided slots 11 and 11a similar to the slots provided in a bolt, that is to say, each of the slots is provided with lateral extensions in one of its sides, the purpose of which is to enable, when the rods have been moved longitudinally away from one another and subsequently rotated, the loops 10 and 10a to be engaged with such extensions in order to retain the rods in the position which by such motion they have been caused to assume.

On the ends of the rods there are provided projections 12 and 12a in the extremities of which recesses 13 and 13a are formed adapted to engage the levers 14 forming part of the duplicating machine, as shown more clearly in Figure 5, whereby the ink distributing rollers co-operating with the cylinders having been removed the scraper element will be secured in position against the cylinders 15 and 15a of the duplicating machine, when it is desired to clean the same or, in other words, remove the ink adhering to them, the arms 6 extending between the cylinders and being engaged in the channels 16 and 16a adjacent to the ends thereof.

The inking cylinders in the construction illustrated are rotatably mounted, see Figures 6, 7 and 8, in the side members 17 and 17a of the frame of the duplicating machine and they are arranged to be rotated by means of a handle 18, shown broken away in Figure 6, through any suitable driving connection, flexible endless bands 19 and 19a being provided for securing a driving connection between the lower and the upper inking cylinders.

On the spindle of the upper inking cylinder pairs of levers 14 and 14a are pivoted. The levers of each pair are connected together by a spring 20 and are associated with a lever 21 pivotally mounted on the pin 22 secured to one of the side members of the frame of the machine and provided with a pin 23 engaging in slots 24 in the levers 14, so that by manipulation of the lever 21 these two levers may be moved about their pivotal connection with the spindle of the upper inking cylinder.

When the ends of the levers are moved apart, as will be seen more clearly from Figures 5 and 7, the cleaning device may, by their aid, be secured in position with the edges of the scraper element bearing firmly against the inking cylinders.

By giving the inking cylinders one complete revolution when the scraper is in this posi-

tion, substantially the whole of the ink will be removed therefrom, the ink being collected upon the scraper element. The cleaning device may then be removed from the machine by rotating the rods 9 and 9a so as to release the handle members 10 and 10a from engagement in the lateral extensions of the slots 11 and 11a thus causing the projections 12 and 12a to move into the position shown in dotted line in Figure 5 and subsequently sliding the rods into the position shown in dotted line in Figures 1 and 2. The scraper element may then be detached from the pins 5 on the frame member and may be cleaned or thrown away.

As will be understood, a line of ink will be left on each of the inking cylinders owing to the fact that, after rotation thereof, the edges of the scraper on which the ink has been accumulated will be in contact with the cylinders but after removal of the cleaning or ink-removing device the small residue of ink on the cylinders may be readily removed with the aid of a duster.

Having now described my invention, what I claim as new and desire to secure by Letters Patent is:

1. Means for removing ink from the inking cylinders of a duplicating machine of the kind in which with a plurality of inking cylinders journaled in a frame there is associated a flexible stencil carrier secured to endless bands whereby the stencil is caused to travel over the inking cylinders comprising a scraper element in the form of a strip of flexible material, the opposite edges of which are adapted to bear against the inking cylinders, a rigid support for the scraper element, arms associated with the rigid support adapted to be brought in position to bear against some stationary portion of the duplicating machine and further arms on the rigid support adapted to extend between the inking cylinders to resist rotational motion being imparted to the device consequent upon rotation of the inking cylinders.

2. Means for removing ink from the inking cylinders of a duplicating machine of the kind in which with a plurality of inking cylinders journaled in a frame there is associated a flexible stencil carrier secured to endless bands whereby the stencil is caused to travel over the inking cylinders comprising a scraper element in the form of a strip of flexible material, a rigid support for the scraper element, guides on said rigid support, rods slidably mounted in said guides, arms on the ends of said rods adjacent to the ends of the rigid support adapted when the rods are extended in their guides, to engage some fixed portion of the duplicating machine and press the opposite edges of the scraper element against the inking cylinders and further arms on the rigid support adapted to extend between the inking cylinders of the duplicating machine and to resist rotational motion being

imparted to the rigid support consequent upon rotation of the inking cylinders.

3. Means for removing ink from the inking cylinders of a duplicating machine of the kind in which with a plurality of inking cylinders journaled in a frame there is associated a flexible stencil carrier secured in endless bands whereby the stencil is caused to travel over the inking cylinders comprising a scraper element in the form of a strip of flexible material, a rigid support for the scraper element, tubular guides on said rigid support, rods slidably mounted in said guides, arms on the ends of said rods adjacent to the ends of the rigid support adapted, when the rods are slid outwards in their guides, to engage some fixed portion of the duplicating machine and press the opposite edges of the scraper element against the inking cylinders, bayonet slots in the tubular guides, projections on the rods adapted to co-operate with said bayonet slots to permit the rods when slid outwards to be rotated about their axes to retain the rods in the said position and further arms on the rigid support adapted to extend between the inking cylinders of the duplicating machine and to resist rotational motion being imparted to the rigid support consequent upon rotation of the inking cylinders.

4. Means for removing ink from the inking cylinders of a duplicating machine of the kind in which with a plurality of inking cylinders journaled in a frame there is associated a flexible stencil carrier secured to endless bands whereby the stencil is caused to travel over the inking cylinders comprising for supporting a flexible scraper element a frame member including a central portion and arms at each end extending at right angles from said central portion adapted to engage between the inking cylinders of the duplicating machine, guides on the central portion of the frame member, rods slidably mounted in said guides, arms extending at right angles from said rods adapted when the rods are slid outward in their guides to engage some fixed portion of the machine and press the opposite edges of the scraper element into firm contact with the inking cylinders of the duplicating machine.

In testimony whereof I have signed my name to this specification.

DAVID GESTETNER.
